UNITED STATES PATENT OFFICE

2,569,222

VACUUM CLEANER

Arnold H. Beede and Leon P. Borkoski, Stamford, Conn., assignors to Electrolux Corporation, New York, N. Y., a corporation of Delaware

Application June 23, 1950, Serial No. 169,964

11 Claims. (Cl. 183—37)

1

This invention relates to a vacuum or suction type cleaner having means adapted to dispose of the dust and dirt accumulated therein. More particularly, it embraces an automatically conditioned tank type cleaner having mechanically actuated self-contained control mechanisms for removing accumulated dirt after such an amount is collected in a porous disposable bag located within the cleaner as is capable of effecting a predetermined change in the operating efficiency of the cleaner.

It is a major object of this invention to provide an improved vacuum cleaner having automatic means for disposing of dust collected in a paper bag by ejecting from the cleaner the porous disposable paper bag filled with dust separated from the suction air stream, the ejection of the dust and dirt filled bag being effected upon the attainment of a predetermined pressure drop within the cleaner.

It is a further and important object hereof to provide completely mechanical means for effecting the automatic operation of the dust bag ejecting devices.

A still further object is to provide a vacuum cleaner having a large dust collecting capacity which operates at a substantially uniform efficiency.

Still other and further objects will be disclosed hereinbelow or will become obvious to those skilled in the art from a study of the following description together with the appended drawings wherein:

Figure 1 is a perspective view of the vacuum cleaner as seen from the air intake end, showing a portion of the hose without the conventional wand and nozzle attachments;

Figure 2 is a sectional view taken on the line 2—2 of Fig. 1 showing the ejector mechanism; the cord plug connection, the motor fan unit and the hose connecting assembly being shown in plan view;

Figure 3 is a partial sectional view taken on the line 3—9, Fig. 1 with the cover closed, showing details of the pneumatic control system, switching means and cover latch;

Figure 4 is a sectional view taken on the line 3—3, Fig. 1, the cover however being shown released to open position;

Figure 5 is a sectional view taken on the broken line 5—5, Fig. 1 with the cover closed, showing details of the automatic and manual means for releasing the cover; and

Figure 6 is a sectional view taken on the broken line 5—5, Fig. 1, the cover however being shown

2

released to open position and showing a portion of the bottom parallel linkage broken away in order to show the internal arrangement of parts more clearly.

It is a feature of this invention that the functioning of the cleaner in its dust disposal capacity is automatic, self-contained and after being one initiated by the establishment of predetermined changes in the operational characteristics of the 10 air suction stream within the cleaner, the entire sequence of operations terminating in the ejection of the dust-filled bag is effected in a series of steps. Thus, with continued dust collection during the regular operation of the cleaner, a 15 pressure difference is gradually built up within the cleaner between the inside and the outside of the dust-collecting bag, i. e. an increase in pressure drop through the bag is gradually built up. This results in a continuous and progressively in- 20 creasing force being exerted upon a pressure differential measuring diaphragm the opposite sides of which are subjected to the different pressures built up on the outside and inside of the dust bag, the chamber on one side of the diaphragm being 25 connected to an opening communicating with the clean side of the dust bag, the chamber on the other side of the diaphragm being connected to an opening communicating with the dirty side of the dust bag. Then, upon the attainment of a 30 predetermined value in the resultant force exerted upon the pressure differential diaphragm, motion is imparted to this diaphragm in response to an increase in pressure drop through the dust bag and at a predetermined distortion the dia- 35 phragm conditions means which sets into operation a series or sequence of mechanically actuated steps which sequence when once initiated culminates in the ejection of the dust-filled bag from the cleaner housing.

In a preferred embodiment, the differential pressure diaphragm mechanically withdraws restraining means in the form of a pair of roller elements which normally hold a pair of tracks in relatively fixed position and between which 40 tracks the roller elements are disposed so as to render or hold inoperative a triggering mechanism in the form of a spring biased bell crank. The release of this bell crank enables the latter to actuate a spring biased cover retaining latching means so as to release the cover which is then 45 free to assume its spring biased open position.

This normally restrained or immobilized bell crank also serves upon release to actuate a circuit deenergizing snap type toggle switch whereby 50 the circuit to the motor fan unit is broken in

timed relation with the opening of the cover. The sequential cover opening steps together with the timely breaking of the motor fan circuit results in a progressive slowing down in motor fan speed and consequently the air suction stream also progressively decreases to a value at which highly effective bag ejection is thereupon more readily attainable.

The automatic dust bag ejection is effected by a spring actuated ejector plate which is held in fully cocked or loaded position by a latch means spring biased to restrain the ejector plate from operation. In the embodiment illustrated an extension on one of a pair of parallel link members hingedly supporting the removable cover, in the terminal travel of the latter towards its fully opened position, serves as a tripping mechanism to actuate the ejector plate restraining latch to its releasing position whereupon the dust-filled bag is expelled from the cleaner housing and deposited on the floor.

Thus, in accordance with this preferred embodiment of the invention, automatic dust bag ejection is effected by mechanical means, after a tripping mechanism is released for operation by a pneumatically actuated pressure differential measuring device. The pressure differential measuring device is conditioned for operation by utilizing the air pressure difference built up within the cleaner casing by dust layers collected and deposited within the dust bag. This pressure difference is established between the inside and outside of the dust collecting bag and is communicated therefrom by appropriate conduit means during the dust collecting process.

Referring now more particularly to the drawings, vacuum cleaner housing 10, Fig. 1, is a hollow casing having a handle 11. It is appropriately supported on a pair of runners 12. The suction or inlet portion of the casing 10 is provided with an air inlet nozzle and wand (not shown) and a flexible hose 13 (partly shown in Fig. 1) and connecting coupling 14 adapted for insertion into hose coupling member 15 mounted on cover 16. Cover 16 effects an air tight seal upon its juxtaposition with reinforcing rubber sealing ring member 19, cardboard disc 31 of dust bag 30 and the (Figs. 5, 6) conventional sealing ring 22 through which the bag is inserted into the cleaner by way of the opening of front body ring 20. Tubular member 21 of the hose coupling assembly 15 is inserted through the opening 32 cut in cardboard disc 31, extends a short distance into the interior of dust collecting receptacle 30, and is sealed against disc 31 by rubber sealing ring 19. Switch button 16a extending through body ring 20 provides the on-and-off manual control and reset button for the cleaner unit.

A perforated sleeve 23 is affixed at one end to front body ring 20 and is adapted to receive within its interior a disposable dust bag 30 of paper construction. This entire unit (sleeve 23, body ring 20, etc.,) is telescopically fitted within the open end of cleaner housing 10 and is affixed therein by retaining screws 24, Figs. 1, 2, etc. In the embodiment shown, sleeve 23 is substantially rectangular in cross-section and is thus adapted to take a bag of substantially similar but slightly smaller cross-section 30.

Dust bag 30, Fig. 2, comprises a dust receptacle of paper or similarly air-pervious, dust-impervious, material 33 affixed at its mouth to the rear surface of a hard paper or cardboard disc 31, the latter of which is clamped between

rubber sealing ring 19 of hose coupling assembly 15 and rubber sealing ring 22 within the open end of front body ring 20. Cardboard disc 31 has a central opening 32 through which tubular member 21 is inserted in order to introduce the air and entrained dust directly into the interior of dust bag 30.

The entire surface of sleeve member or dust bag compartment 23 is provided with apertures 27, Fig. 2, in order to permit suction current free passage therethrough and into chamber 40. Sleeve member 23 contains the ejector unit 51 and its associated expulsion spring 53. From chamber 40, the suction air current passes through conduit 50, motor housing 70 which contains mounted therein motor 71, after which the suction current passes through fan housing 73 containing fan 72 and out through louver openings 74.

The bag ejector mechanism 51, 53, Fig. 2, for operating the bag ejector plate 52, is in the form of a spiral compressible spring 53 which can be collapsed into fully flexed or loaded condition by pushing ejector plate 52 back into the cleaner housing until latch 52a engages opening 52b in ejector plate 52. U-shaped frame member 55 affixed to the rear end of perforated sleeve 23 supports the fixed end mounting 56 of the ejector spring 53.

Latch pin 52a is held in restraining position by lever 61 fulcrummed at 61a and maintained in ejector restraining position by biasing spring 62. Latch 52a is operated or actuated to releasing position by automatic triggering effected by the extension 63 of parallel cover linkage 17. Thus, with this particular latching device for restraining the ejector mechanism 51, plate 52 is held in loaded position until cover 16 is practically fully opened. Cover 16 is normally held closed by latch (bell crank) 100, Figs. 3, 4, fulcrummed at 101 and biased to retain cover 16 in closed position by spring 102. Latch 100 holds cover 16 by projecting lug 103.

The cover may be opened for inspection of the dust bag and its contents by pressing release button 16b, Figs. 1, 5 and 6, mounted on the front surface of cover link member 16c. Pressing button 16b inwards causes plunger 105 mounted in guide member 106 and biased outwardly by spring 108 to contact latch actuating pin 99 and through extension lug 99a to thereby release cover restraining latch 100.

Latch 52a can be tripped only when cover 16 is fully opened and hence compression and jamming of bag 30 within sleeve member 23 is impossible.

It is to be noted that pneumatically operated device 200, Figs. 3, 4, releases bell crank 250 one arm of which is in the form of a movable track 251 affixed to a shaft 252 bearinged in mounting members 253, 254 the other arm 255 is affixed to shaft 252 and provided with unidirectionally actuating finger 255a pivoted at 255b and biased to operating position by spring 255c. Finger 255a trips cover restraining latch 100 by actuating arm 110 thereof. Arm 251 of bell crank 250 also actuates toggle switch 310 to its "off" position through a mechanical connection including link member 96 which actuates switch arm 97 through pin 98, thereby stopping the motor fan unit and thus deenergizing the cleaner unit.

The pneumatic control means 200 measures the increased pressure drop through the bag accompanying continued dust collection and triggers the mechanical cover releasing means 100.

It comprises a two chambered element 201, 202 separated by a diaphragm 203 biased by spring 204 to forward position. Chamber 201 is connected pneumatically by tube 205 to the clean surface of dust bag 30 while chamber 202 is connected by tube 206 to the dirty surface of dust bag 30 by way of tubular member 21.

Connecting rod 210 has one end affixed to and movable with the center of diaphragm 203 so as to convey motion therefrom to a pair of rollers 211, 212 bearinged in end pieces 213, 214 and adapted to ride on fixed track 220 and movable track 251. When extended, rod 210 causes rollers 211, 212 to hold the movable track in relatively fixed position and when retracted releases the movable track for movement with respect to the fixed track in response to the biasing action of spring 256.

Cover 16, Figs. 1, 2, 5, is hingedly supported at 17b and 16e from front body ring 20 by means of a pair of parallel links, one link 17 being pivoted at 17a, while the second link is the lower portion of front cover member 16c pivoted at 16d. A spring 13, Fig. 5, maintains the cover 16 biased to its open position. The extension 63 of link 17 has a unidirectionally actuating finger 63a pivoted at 63b, is biased to operating position by spring 63c and functions as above described to release latch 52a and effect dust bag ejection only upon downward travel and substantially full opening of cover 16.

The tripping device for operating the cover releasing mechanism in the embodiment illustrated is independent of the ejection unit 51. As illustrated in the drawings, Figs. 3, 4, 5 and 6 pressure difference diaphragm 200 releases bell crank triggering mechanism 250, Figs. 3, 4, 5 and 6 which trips the normally spring biased cover restraining latch 100. The normally restrained cover triggering mechanism also actuates switch 310 which breaks the motor fan circuit in timed relation, cutting off the power supply to the motor fan unit. It is the release of the cover, in its terminal travel towards opened position, that actuates the restraining means 52a holding the bag ejecting means 52 from action.

Housing 10 is preferably assembled from three large die castings, namely an upper casting 10a, a middle casting 10b and a lower or base casting 10c, all held together by appropriate fastening means, e. g., machine screws, bolts, etc., as shown at 24, Fig. 2. Rubber sealing rings 10d are used where necessary in order to attain more perfect assurance against air suction leakage and hence effect better dust collection.

With the dust bag 30 in place and cover 16 closed as in Fig. 3, the motor fan unit is started by pressing button 16a which actuates toggle switch 310 to its "on" position. If bell crank 250 is in the position shown in Figs. 4 and 6, actuation of switch button 16a causes ring 310a to depress lever member 96 and reset or return movable track 251 to its relatively fixed position shown in Figs. 3 and 5 with rollers 211, 212 out of notch 251a. The cleaner is then in condition for operation and automatic bag ejection.

Thus, this invention provides a simplified control system for enabling a pneumatically triggered device to effect the automatic operation of a predetermined control mechanism or to initiate a sequence of steps in a device such as a vacuum cleaner or a similarly suction or pressure operated piece of apparatus.

More specifically, means is provided for use in a vacuum cleaner whereby pneumatic and mechanical controls are used to trigger such elements as

sealing means in the form of a movable cover, or energizing and deenergizing means in the form of a toggle switch, etc., etc., all of which are operated or actuated in response to and upon the establishment of, predetermined pressure conditions within the cleaner.

It is to be understood that the embodiment herein specifically described is to be considered as an illustrative and not limitative disclosure of the invention, the scope of which is more clearly defined by the appended claims.

We claim:

1. In a vacuum cleaner, the combination comprising a casing having an opening, means movable relative to said opening, a hose connector carried by said movable means, means for producing a flow of air through said casing, a dust bag in said casing in the path of said air flow for separating entrained dirt from said air, a member movable in response to an increase in pressure drop through said bag, a fixed track, a movable track, resilient means tending to move said movable track with respect to said fixed track, roller means disposed between said tracks for holding the latter in relatively fixed position, said roller means being displaceable by movement of said movable member to release said movable track for movement with respect to said fixed track, and control mechanism operative in response to movement of said movable track to effect movement of said first mentioned means.

2. In a vacuum cleaner, the combination comprising a casing having an opening, means for producing a flow of air through said casing, a dust bag in said casing in the path of said air flow for separating entrained dirt from said air, releasable means for ejecting said dust bag, a member movable in response to an increase in pressure drop through said bag, a fixed track, a movable track, resilient means tending to move said movable track with respect to said fixed track, roller means disposed between said tracks for holding the latter in relatively fixed position, said roller means being displaceable by movement of said movable member to release said movable track for movement with respect to said fixed track, and means for operating the releasable means for ejecting the dust bag in response to movement of said movable track.

3. In a vacuum cleaner, the combination comprising a casing having an opening, a movable cover for said opening, means for producing a flow of air through said casing, a dust bag in said casing in the path of said air flow for separating entrained dirt from said air, a member movable in response to an increase in pressure drop through said bag, a fixed track, a movable track, resilient means tending to move said movable track with respect to said fixed track, roller means disposed between said tracks for holding the latter in relatively fixed position, the roller means being displaceable by movement of the movable member to release the movable track for movement with respect to the fixed track, and means for opening said movable cover in response to movement of the movable track.

4. In a vacuum cleaner, the combination comprising a casing having an opening, a movable cover for said opening, means for producing a flow of air through said casing, a dust bag in said casing in the path of said air flow for separating entrained dirt from said air, releasable means for ejecting said dust bag, a member movable in response to an increase in pressure drop

through said bag, a fixed track, a movable track, resilient means tending to move said movable track with respect to said fixed track, roller means disposed between said tracks for holding the latter in relatively fixed position, the roller means being displaceable by movement of the movable member to release the movable track for movement with respect to the fixed track, means for opening said movable cover in response to movement of the movable track, and means for operating the releasable means for ejecting the dust bag in response to movement of said cover.

5. In a vacuum cleaner, the combination comprising a casing having an opening, means for producing a flow of air through said casing, a dust bag in said casing in the path of said air flow for separating entrained dirt from said air, switching means for energizing and deenergizing said air flow producing means, a member movable in response to an increase in pressure drop through said bag, a fixed track, a movable track, resilient means tending to move said movable track with respect to said fixed track, roller means disposed between said tracks for holding the latter in relatively fixed position, said roller means being displaceable by movement of the movable member to release the movable track for movement with respect to the fixed track, and means for actuating said switching means for deenergizing the air flow producing means in response to movement of said movable track.

6. In a vacuum cleaner, the combination comprising a casing having an opening, means for producing a flow of air through said casing, a dust bag in said casing in the path of said air flow for separating entrained dirt from said air, switching means for energizing and deenergizing said air flow producing means, releasable means for ejecting said dust bag, a member movable in response to an increase in pressure drop through said bag, a fixed track, a movable track, resilient means tending to move said movable track with respect to said fixed track, roller means disposed between said tracks for holding the latter in relatively fixed position, said roller means being displaceable by movement of the movable member to release the movable track for movement with respect to the fixed track, and means for actuating said switching means for deenergizing the air flow producing means and for operating the releasable means for ejecting the dust bag in response to movement of said movable track.

7. In a vacuum cleaner, the combination comprising a casing having an opening, a movable cover for said opening, means for producing a flow of air through said casing, a dust bag in said casing in the path of said air flow for separating entrained dirt from said air, switching means for energizing and deenergizing said air flow producing means, releasable means for ejecting said dust bag, a member movable in response to an increase in pressure drop through said bag, a fixed track, a movable track, resilient means tending to move said movable track with respect to said fixed track, roller means disposed between said tracks for holding the latter in relatively fixed position, said roller means being displaceable by movement of the movable member to release the movable track for movement with respect to the fixed track, and means for actuating said switching means for deenergizing the air flow producing means, for opening said movable cover and for operating the re-

leasable means for ejecting the dust bag in response to movement of said movable track.

8. In a vacuum cleaner, the combination comprising a casing having an opening, means for producing a flow of air through said casing, a dust bag in said casing in the path of said air flow for separating entrained dirt from said air, releasable means for ejecting said dust bag, a member movable in response to an increase in pressure drop through said bag, a fixed track, a movable track, resilient means tending to move said movable track with respect to said fixed track, roller means disposed between said tracks for holding the latter in relatively fixed position,
- 10
- 15
- 20

9. In a vacuum cleaner, the combination comprising a casing having an opening, a movable cover for said opening, means for producing a flow of air through said casing, a dust bag in said casing in the path of said air flow for separating entertained dirt from said air, releasable means for ejecting said dust bag, 25 a member movable in response to an increase in pressure drop through said bag, a fixed track, a movable track, resilient means tending to move said movable track with respect to said fixed track, roller means disposed between said tracks 30 35 for holding the latter in relatively fixed position, a roller receiving notch in one of said tracks, the roller means being displaceable by movement of said movable member to enter said notch and release said movable track for movement with respect to said fixed track, and means for opening said movable cover and for operating the 40 releasable means for ejecting the dust bag in response to movement of said movable track.

10. In a vacuum cleaner, the combination comprising a casing having an opening, a motor fan unit for producing a flow of air through said casing, a dust bag in said casing in the path of said air flow for separating entrained dirt from said air, a circuit for energizing said motor fan unit, a manual switch for opening and closing said circuit, a member movable in response to an increase in pressure drop through said bag, a fixed track, a movable track, resilient means tending to move said movable track with respect to said fixed track, roller means disposed between said tracks for holding the latter in relatively fixed position, said roller means being displaceable by movement of the movable member to release the movable track for movement with respect to the fixed track, means for opening said switch in response to movement of said movable track, and means responsive to subsequent manual closing of said switch for returning said movable track to its original position with respect to said fixed track.

11. In a vacuum cleaner, the combination comprising a casing having an opening, a movable cover for said opening, means for producing a flow of air through said casing, a dust bag in said casing in the path of said air flow for separating entrained dirt from said air, releasable means for ejecting said dust bag, a member movable in response to an increase in pressure drop through said bag, a fixed track, a movable track, resilient means tending to move said movable track with

respect to said fixed track, roller means disposed between said tracks for holding the latter in relatively fixed position, a roller receiving notch in said movable track, the roller means being displaceable by movement of said movable member to enter said notch and release said movable track for movement with respect to said fixed track, and means for opening said movable cover and for operating the releasable means for ejecting the dust bag in response to movement of said movable track.
